UNITED STATES PATENT OFFICE.

ERNEST N. HUMPHREY, OF NEW BRITAIN, CONNECTICUT, ASSIGNEE TO THE TRAUT & HINE MANUFACTURING COMPANY, OF NEW BRITAIN, CONNECTICUT, A CORPORATION OF CONNECTICUT.

SAFETY-RAZOR.

1,076,429.

Specification of Letters Patent.

Patented Oct. 21, 1913.

Application filed November 11, 1912. Serial No. 730,577.

To all whom it may concern:

Be it known that I, ERNEST N. HUMPHREY, a citizen of the United States, residing at New Britain, county of Hartford, 5 Connecticut, have invented certain new and useful Improvements in Safety-Razors, of which the following is a full, clear, and exact description.

My invention relates to safety razors.

10 It has for its object to provide a folding safety razor.

It also has for its object to provide a safety razor in which the blade has means at the rear edge thereof coacting with the 15 holder for defining the position of the blade in the holder.

It also has for its object to provide a 20 razor having spring-pressed means for retaining the blade in position when first inserted and means for subsequently securing the blade in place.

It also has for its object to provide such a 25 razor with a finger-piece upon a spring-pressed folding plate for retracting said plate.

The following is a description of an embodiment of my invention, reference being had to the accompanying drawings, in which—

30 Figure 1 shows a front elevation of the razor with the parts in position for use. Fig. 2 shows a front elevation of the same with the parts in position so that the blade can be removed. Fig. 3 shows a side elevation of the razor with the parts in position for use. Fig. 4 shows a longitudinal section of the upper part of the same on the line $\alpha-\alpha$ Fig. 3. Fig. 5 shows a plan view of the 35 razor with the blade removed. Fig. 6 shows an end view of the handle, looking downward.

Referring more particularly to the drawings, 1 is a handle pivoted at 2 to a frame 3. This frame has an extended base portion 4 45 from which extend arms 5 carrying projections 6, said projections lying in a plane parallel to the surface of the extended portion 4.

7 is a plate having a lip or guard 8 provided with holes 9 to permit the passage of the lather therethrough. Between this plate and the base is a spring 10, the free ends of the same bearing against the extended portion 4 and having projections 11 which pass 50 through holes therein. This spring on each side of its central portion bears against the

plate 7 and is provided with a hole 12 permitting the upper end of the handle 1 to engage with the plate 7 and hold it firmly in place when the parts are in shaving position. 60 The plate 7 is provided with a projection 13 adapted to engage a corresponding recess in the end of the handle 1 so as to lock the handle in position. The plate 5 is provided with a recess 14 at its rear end in which an 65 enlargement 14 on the rear of the blade 15 fits so as to define the position of the blade so far as endwise movement is concerned. The plate 7 is provided with a finger-piece 16, by which, when the parts are in the position shown in Fig. 2, the plate 7 can be easily depressed against the action of the spring 10, so as to allow the easy removal of the blade. The extremities of the guard are provided with slight projections 17 which 70 project in front of the corners of the blade 75 so as to prevent them from digging into the flesh of the user.

In inserting the blade into the holder, the parts are swung into the position shown in 80 Fig. 2 and the blade is inserted therein from the rear, the spring 10 yielding so as to permit such insertion. The frame is then moved to the position shown in Fig. 1, whereupon the projection 13 engages with 85 the recess in the upper end of the handle locking the parts in the position shown in Fig. 1, and securely holding the blade in place so that all the parts are rigidly connected. In removing the blade the parts are 90 swung into the position shown in Fig. 2, whereupon the plate may be lowered by pressure exerted by the thumb upon the projection 16, permitting the easy removal of the blade from the rear. 95

The embodiment shown permits of various modifications without departing from the spirit of my invention or the scope of the appended claims.

What I claim is:

100 1. In a razor, the combination of a frame and a blade, said frame having portions fixed relative to one another extending on both sides of the blade and a handle in the frame, a plate located between the end of the handle and the blade, and a spring between the plate and the portion of the frame adjacent to the handle and tending to move said plate away from the handle and toward said blade and a part of the frame remote from the handle, the handle being movable relatively to the frame to exert pressure on 105 110

said plate and hold the blade rigidly in place.

2. In a razor, the combination of a frame and a blade, said frame having portions extending on both sides of the blade and a handle in the frame, a plate located between the end of the handle and the blade, and a spring between the plate and the portion of the frame adjacent to the handle and tending to move said plate away from the handle and toward said blade and a part of the frame remote from the handle, the handle being movable relatively to the frame to exert pressure on said plate and hold the blade rigidly in place, said spring having a hole in its central portion so that said handle can engage said plate directly.

3. In a razor, the combination of a frame and a blade, said frame having portions ex-

tending on both sides of the blade and a handle pivoted in the frame, the end of said handle when the frame is swung into shaving position holding the blade rigidly in place, a plate located between the end of the handle and the blade, and a spring between the plate and the portion of the frame adjacent to the handle and tending to move said plate away from the handle and toward said blade and a part of the frame remote from the handle, said plate having a projection forming a thumb-piece for the depression of said plate against the action of said spring when said frame is in non-shaving position.

ERNEST N. HUMPHREY.
